Primary Examiner — Catherine S Posthauer(74) *Attorney, Agent, or Firm* — Jacob M. Ward; Ward Law Office LLC(57) **CLAIM**

The ornamental design for a shipping tray for bench, as shown and described.

DESCRIPTION

FIG. 1 is a top perspective view of a shipping tray for bench; FIG. 2 is a bottom perspective view thereof; FIG. 3 is a top plan view thereof; FIG. 4 is a bottom plan view thereof; FIG. 5 is a front elevational view thereof; FIG. 6 is a rear elevational view thereof; FIG. 7 is a left-side elevational view thereof; and, FIG. 8 is a top perspective view thereof, shown in use with a stack of exemplary benches. A right-side elevational view of the shipping tray is not shown as it is a mirror image of the left-side elevational view shown in FIG. 7. The broken lines shown in FIG. 8 are for the purpose of illustrating the environment and form no part of the claimed design.
